HARRY S. McCORMACK, OF NEW ROCHELLE, NEW YORK, ASSIGNOR TO UNDERWOOD TYPEWRITER COMPANY, OF NEW YORK, N. Y., A CORPORATION OF DELAWARE.

PAPER-ROLL CRADLE.

1,144,769.

Specification of Letters Patent. Patented June 29, 1915.

Application filed December 10, 1910. Serial No. 596,586.

To all whom it may concern:

Be it known that I, HARRY S. McCORMACK, a citizen of the United States, residing in New Rochelle, in the county of Westchester and State of New York, have invented certain new and useful Improvements in Paper-Roll Cradles, of which the following is a specification.

This invention relates to means for supporting paper webs or rolls from which the paper is led to the platen of a typewriting machine, and it constitutes an improvement on a portion of the invention disclosed in United States Letters Patent No. 953,854, granted to me April 5, 1910.

One object of this invention is to simplify and improve paper roll holding devices by providing a separate support for each roll, the support and roll constituting a unit which may be applied to or removed from the machine irrespective of other similar units.

Another object of this invention is to enable the use of webs of various widths and diameters with the same paper web support or cradle. This is accomplished by making the roll-supporting cradles adjustable both as to length and as to breadth, the ends of said cradles being connected by rods adjustable in length and mounted in extensible arms secured to the ends to accommodate rolls of different diameters. By means of this arrangement also, machines may be fitted with cradles of a size designed to support rolls of the particular size or sizes used by the customer, thereby eliminating the necessity for making cradles of varying sizes or keeping a large stock of cradles on hand. The cradles may be provided for endwise extension without being adjustable widthwise, and vice versa.

Other objects and advantages will herein-after appear.

In the accompanying drawings, Figure 1 is a rear perspective, showing the paper roll cradles, the webs being led therefrom over the guides and around the platen of an Underwood writing machine. Fig. 2 is a plan of a pair of cradles, the one on the right being extended to accommodate a roll thicker in diameter than the one shown at the left. Fig. 3 is an end view showing the manner of adjusting the cradle to rolls of different diameters. Fig. 4 is a side view, showing the manner of attaching the cradles to the

machine. Fig. 5 is a section through a paper roll. Fig. 6 is a detail showing a sectional connecting rod of the cradle, disassembled with the cradle standards.

A carriage 1 travels back and forth on a main frame 2, having legs 3 to which feet 4 are secured by screws 5. The carriage supports a platen frame including a paper shelf 6, in which is mounted a platen 7.

Horizontal rolls or webs of paper 8, 9 and 10 are located in rear of the machine with their axes extending rearwardly at right angles to the platen. From these rolls, the webs 11, 12 and 13 are led upwardly to the left (in Fig. 1) to a horizontal rearwardly extending guide bar 14 fixed to the carriage 1, parallel with the rolls.

The webs turn around over the top of said guide bar 14 and thence run to a second horizontal guide 15 extending at an angle of about 45 degrees to the guide bar 14, the apex of the angle being at the rear ends of said guides. The webs dip beneath the guide 15 and fold over the same, whereby their direction of travel is changed to run at right angles to the direction in which they are led from the rolls. Thence the webs are led under the platen 7. Certain of the rolls, as roll 9, may consist of carbon paper to make copies on web 13 of the original writing on web 11, or all of such rolls may be record rolls and the writing on the original web be copied on the remaining webs in some other manner.

The web controlling guides 14, 15 are preferably formed of a single length of wire bent at 14^a to give the required angle, their forward ends being secured to collars 15^a, adjustably secured by set screws 1^b on a rod 1^a connected to the carriage 1.

The webs are unwound from the rolls 8, 9 and 10 during the return of the carriage 1 to begin a new line, the webs hanging loosely from the bar 14 during the writing of a line to eliminate drag on the carriage.

To enable the operator to maintain a compact device with no unnecessary parts, as when less than the full number of rolls are employed; and to adjust the rolls relatively to the limits of travel of the platen to reduce the length of slack web, each roll is mounted in a separate cradle detachably connected to the machine. Each cradle preferably comprises a pair of ends or standards 16 having feet 17 resting on a table or support 18 and

connected by rods 19 extending about parallel with each other between the opposite ends of the standards. The axles 20 of said rolls fit in bearings 21 formed intermediate the ends of each standard. The cradle may be releasably connected to a bar or support 22 extending about parallel with the platen, and connected to the main frame 2 by the screws 5 passing through arms 24 on the bar.

10 The cradles may have one or more hooks 23 carried by one of the standards 16 to catch over said bar at any part of its length, to hold the cradle and roll against accidental displacement due to the pull on the roll when the carriage is returned to the beginning of a line. One or more cradles carrying their paper rolls may be attached one behind the other along the bar 22, (Figs. 1 and 2), the bar being sufficiently long to enable additional cradles to be added if desired. Upon the removal of one or more of a series of cradles, the remainder may be adjusted along the bar to reduce the length of slack web, caused by the travel of the carriage in letter-spacing direction. The rolls 8, 9, 10, (formed by webs wound on hollow tubes 9^a), are supported on the axles 20 between heads 25 having conical or tapering core sections 26, (through which the axle 20 extends) to enter the opposite ends of the tube or bore 9^a of a roll, (see Fig. 5). These cones aid in keeping the roll of paper nicely centered and away from contact with the standards, so that easy and certain unrolling is effected. This is very necessary in the case of so sensitive a mechanism as a rapidly operated typewriting machine. The axle 20 is sufficiently long to support rolls of different lengths, the heads 25 being adjustably held on the axle by set screws 27 passing through hubs 28 on the heads. The axles 20 with their heads 25 and core sections 26 form spools for the rolls.

45 The distance between the standards of a cradle may be increased or decreased to accommodate rolls of paper of different lengths, (bearing webs of different widths) by fitting the connecting rods 19 with detachable sections 19^a, at least one end of which rod being detachably secured to the adjacent standard. Referring to Figs. 1 and 2, the main sections 19 of the connecting rods are each rigidly secured at one end to one of the standards 16 of the cradle, the cradle being adjusted as to length by the addition of extension sections 19^a to or their removal from the free end of said main section, fastening means, as screws 29, entering threaded sockets 30 in the outermost sections 50 19^a of the rods, to connect them to the opposite standard of the cradle.

In Fig. 6, the main section 19 is releasably secured to the adjoining standard 16 by a threaded boss 19^b passing through the 55 standard and secured by a nut 31. In either

construction, the sections 19^a may be connected together and to the main section, by male and female threaded couplings, comprising bosses 19^b and sockets 30, as shown in Fig. 6. The removable sections each have 70 openings 32 into which a suitable tool may be inserted to release them from or secure them tightly to the adjacent sections.

The cradles are also adjustable as to breadth to accommodate rolls of different diameters, by mounting the opposite ends of the connecting rods 19 in ears 33 adjustably connected to the respective standards 16, as by set screws 34 and slots 35. By loosening the set screws 34, the ears may be drawn out 75 endwise in opposite directions to project substantially horizontally beyond and about in alinement with the ends of the standards, thereby moving the connecting rods 19 away from the bearings 21 of the axle and 80 from each other, to accommodate rolls of larger diameter, the set screws 34 being tightened, when the rods have been sufficiently separated, to hold the ears where adjusted.

90 In Figs. 2 and 3, the extensible ears 33 are mounted on the inner face of one standard and on the outer face of the opposite standard (to afford ready access to the set screws 34 and to the fastening screws 29 when the latter are used) the ends of that standard having the ears on its outer face being recessed at 36 (Fig. 3) to afford clearance for the connecting rods 19 when the cradle is contracted to its minimum width.

95 Side guides or gages 37 for the opposite edges of the web or webs 11, 12 and 13 may be removably and adjustably secured to the guide bar 14, said gages, in the present instance, comprising disks 37 having hubs 38, 105 the disks and hubs being slotted at 39 to be slipped onto or off from the guide bar transversely thereof, and held where adjusted by set screws 40.

Variations may be resorted to within the 110 scope of the invention, and portions of the improvements may be used without others.

Having thus described my invention, I claim:

1. A paper roll cradle comprising a pair 115 of standards, and rods connecting said standards, said rods being between the standards and detachably connected thereto, each rod comprising a series of sections detachably connected to render the cradle 120 adjustable to rolls of different lengths.

2. A paper roll cradle comprising a pair 125 of standards, rods connecting and supporting said standards, each of said rods comprising a series of sections detachably connected to render the cradle adjustable to rolls of different lengths, said rods being adjustable inward and away from each other by means on the frame, to accommodate rolls of different diameters, said rods and 130

standards being provided with clamping means.

3. A paper roll cradle for use with a typewriting machine, said cradle comprising a pair of end standards, each of said end standards having a pair of oppositely adjustable ears, rods secured to the ears, and between the standards, and connecting the ends, and means for securing the ears in adjusted positions.

4. A paper roll cradle for use with a typewriting machine, said cradle comprising a pair of ends, said ends comprising standards having bearings for the axle of a roll, oppositely adjustable ears secured upon said standards, means to secure the ears where adjusted, to the standards, and rods between the standards connecting the ears of one standard to the corresponding ears of the opposite standard.

5. A paper roll cradle for association with a typewriting machine, said cradle comprising a pair of ends, rods connecting the ends, said rods formed of a series of sections detachably connected to adjust the cradle to rolls of different lengths, each detachable section being fitted to receive a tool for engaging or disengaging the sections.

6. A roll carrying cradle for use with a typewriting machine, comprising ends carrying journals for said roll, a rod extending from one end, a removable extension for said rod, and means to hold either the rod or said extension to the opposite end.

35 7. A roll carrying cradle for use with a typewriting machine, comprising end members, carrying journals for said roll, a rod forming a rigid connection between the end members, said rod being in sections, each having at one end a threaded projection and at the other a screw, and suitable means for connecting said sectional rod to the end members.

8. A roll carrying cradle for use with a typewriting machine, comprising ends carrying journals for said roll, an axle for said roll, cone centering members on said axle, fasteners holding said centering members

adjusted on said axle, and rods holding said ends, said rod being within opposite ends and being also sectionally adjustable to conform to the adjustment of the centering members.

9. A roll cradle attachment or device to be used with typewriting and other machines, comprising a rod to be attached to said machine, a hook to fit over said rod, and a foot on said cradle to rest on a support to sustain the weight of said cradle, said hook enabling said cradle to be removed by merely lifting from the rod.

10. A roll cradle attachment or device to be used with typewriting and other machines comprising a rod to be attached to said machine, a hook to engage said rod and to be released from said rod by lifting, a foot to rest on a support to sustain the cradle, end pieces forming extensions of said hook and foot respectively, side rods, and adjustable connections between said side rods and said ends.

11. A paper roll cradle comprising vertical end plates forming standards, slots in said standards, an axle shaft in said slots, cones slidably mounted on said shaft, means for securing said cones in position, disks secured to said cones to form spool flanges and rods rigidly connecting said standards, said rods being made in sections to secure adjustment of the standards in accordance with the width and position of said cones.

12. A paper roll cradle comprising vertical end plates forming standards, an axle shaft removably mounted in said standards, rods rigidly connecting said standards and comprising removable sections to adjust the distance between the standards, cones slidably mounted upon said shaft, and means to secure said cones in adjusted position, the adjustment of the distance between the standards being in conformity with the adjustment of the cones.
